UNITED STATES PATENT OFFICE.

HERMAN KERNGOOD, OF BALTIMORE, MARYLAND, ASSIGNOR TO THE ELECTUS FASTENER COMPANY, OF HOBOKEN, NEW JERSEY.

DESIGN FOR A CAP-BLANK FOR CAP-AND-STUD FASTENERS.

SPECIFICATION forming part of Design No. 32,251, dated February 20, 1900.

Application filed January 16, 1900. Serial No. 1,697. Term of patent 14 years.

To all whom it may concern:

Be it known that I, HERMAN KERNGOOD, a citizen of the United States of America, and a resident of 611 Monroe street, city of Baltimore, State of Maryland, have invented a certain new and original Design for a Cap-Blank for Cap-and-Stud Fasteners, of which the following is a specification.

My new and original design relates to the configuration of a cap-blank for cap-and-stud fasteners, illustrated in the accompanying drawings, in which—

Figure 1 is a perspective view of a cap-blank for stud-and-cap fasteners, showing the design. Fig. 2 is a plan view thereof.

1 is the base of the device in the form of a cap. 2 is the tubular socket portion rising therefrom, which is formed with the teat or nipple 3. The sides of the flange have outwardly-swelling curved edges 4, and the ends of the flange are formed with recesses 5, hav-

ing curved inner ends 6, and a projection 7 between said recesses 5, the material or leading feature of the design consisting of the cap-blank having a cylindrical body and cylindrical teat integral with the body and located on one end of it and a horizontal flange at the other end provided with recesses on each side of the flange, having curved bottoms, all as shown.

Having described my invention, what I claim as new, and desire to secure by Letters Patent, is—

The design for a cap-blank for stud-and-cap fasteners, as herein shown and described.

Signed by me at the city of Baltimore, State of Maryland, this 6th day of January, 1900.

HERMAN KERNGOOD.
